HAIR CURLER

Ragnvald G. Leland, New York, N. Y.

Application June 14, 1940, Serial No. 340,438

10 Claims.

(Cl. 132—33)

This invention relates to hair curlers and has for an object to provide an improved construction designed for home use and wherein curls may be made close to the scalp and retained in this position until set.

Another object of the invention is to provide a hair curler formed substantially flat throughout and provided with means for receiving a pair of tying elastic bands arranged so that either band may be looped over a given curl according to which band is next to the scalp.

An additional object is to provide a hair curler in which a coiled bunch of hair is tied by an elastic band and held in place during the time the curler body is being removed and as long thereafter as desired.

In the accompanying drawing—

Fig. 1 is a face view of a hair curler disclosing an embodiment of the invention, one of the elastic bands being partly removed;

Fig. 2 is an edge view of the structure shown in Fig. 1;

Fig. 3 is an end view of the structure shown in Fig. 1 with the elastic bands removed;

Fig. 4 is a plan view of one of the elastic bands shown in Fig. 1;

Fig. 5 is a view similar to the left-hand end illustrated in Fig. 1 showing how the end of a bunch of hair is fitted between the jaws of the curler;

Fig. 6 is a view of the curler with a bunch of hair coiled thereon;

Fig. 7 is a view similar to Fig. 6 but showing one of the elastic bands looped over the coiled hair for tying the same;

Fig. 8 is a view in perspective showing the coiled hair and the curler immediately after the curler has been removed;

Fig. 9 is a perspective view of the elastic band when in tying position;

Fig. 10 is a perspective view of a coil of hair showing the collapsed position of the T-shaped head of the flexible resilient tying member as it is pulled through the coiled hair.

Referring to the accompanying drawing by numerals, the curler is provided with a flat body 1 merging into flat jaws 2 and 3. The body 1 and jaws 2 and 3 may be made of metal, wood, or other material, but is preferably made of a transparent or translucent plastic material, as for instance, a cellulose ester, such as cellulose acetate or nitrate of pyroxalin. The body 1 is flat but at the end opposite the jaws 2 and 3 it is provided with portions or parts 4 and 5 which are bent at opposite angles. These portions are provided

with pointed extensions 6 and 7, whereby notches 8 and 9 are presented. By reason of the fact that the parts 4 and 5 are bent at the angles just mentioned, one run of band 11, namely run 5 10 as shown in Fig. 2, is spaced from the body 1, whereby the fingers of the operator may readily be inserted into the band.

As illustrated particularly in Fig. 2, the elastic tying member 11 is provided with runs 10 and 10 12. At one end it merges into a substantially straight handle 13 and at the other end into a T-shaped anchor 14. The elastic tying member 11 is made of flat material and has the obverse and reverse faces arranged parallel.

15 As shown in the drawing, there are provided two tying members, one for each edge of the hair curler. This is very desirable because when a bunch of hair 15 is inserted between the walls 16 and 17 and then the curler is rotated for 20 winding the hair, one edge of the curler will naturally be close to the scalp when the winding is completed. In order to hold the bunch of hair 15 close to the scalp, the tying member 11 nearest the scalp is swung over as indicated in Fig. 7. The anchor end 14 is held secured while the end 13 of the tying member is disengaged from the body 1 and thereafter the end 13 is passed over and engaged with the anchor end 14, as 25 illustrated in Fig. 7, after which the body 1 is removed from the coiled hair 15, whereby the coiled hair will remain in its desired location held in coiled condition by the tying member. The tying member 11 will appear as shown at the left in Fig. 8.

30 Each of the jaws 2 and 3 is provided with a notch 18 in the free end. The material 19 forming the outer part of the notch is projected beyond the material 20 forming the inner part of the notch. This allows the end of the tying member to be slipped into the notch with ease 35 and then stretched and placed in position as shown in Figs. 5 and 6. The body 1 and jaws 2 and 3 are preferably slightly resilient and by reason of the aperture or opening 21 and apertures 22 and 23, the jaws may be swung apart 40 sufficiently to allow the desired quantity of hair to be inserted between the walls 16 and 17, as shown in Fig. 5. The walls 16 and 17 merge into the curved walls 24 and 25 which extend

45 to the free end of the jaws and thereby provide a large cavity or notch 26, whereby the handle end of the tying member may be readily swung over the free end of the jaw and allowed to move to the position shown in Fig. 7. This completes 50 the operation of coiling and tying the coiled hair.

It is then merely necessary to remove the curler as indicated at the right in Fig. 8.

It will be understood that after the hair has been coiled the desired tying member 11 is grasped, as shown at the right in Fig. 1, and then this member is swung over until it assumes the position shown in Fig. 7. The other tying member is left in place and when the curler is again used a new tying member is provided for the side of the curler not having a tying member. The tying member being soft resilient rubber may be readily left in position in the coiled hair for any desired length of time, as for instance overnight. The tying members being rubber will not be objectionable while sleeping.

When it is desired to remove the tying member, the handle 13 is grasped and pulled to the left, as shown in Fig. 8, and the same will readily slip over the anchor 14. The handle 13 and associate parts are then swung to the right. The tying member 11 may then be readily pulled through the coiled hair without disturbing the same as shown in Fig. 10.

I claim:

1. A hair curler including a body of flat slightly elastic material formed with a pair of slightly spaced jaw members between which the end of a bunch of hair is adapted to be inserted, each of said jaw members having a notch in the outer end, said body at the end opposite said jaw members having a pair of spaced notches and an elastic loop adapted to be positioned in each pair of notches, said elastic loops being arranged so that each loop will be held by one notch at the end of the body and one notch at the free end of a jaw.

2. A hair curler as set forth in claim 1, characterized by forming the free ends of the jaws with a long and a short finger on opposite sides of each of the notches.

3. A hair curler including a flat body merging into two flat resilient jaws, each jaw at the free end having a notch, said body at the end opposite the jaws having a notch for each of the notches on the jaws and an elastic rubber member for each pair of notches, each of said rubber members having an elongated loop, an enlargement at one end and a handle at the other end.

4. In a hair curler, an elastic rubber hair tying member formed with a substantially elongated loop, an elongated solid handle extending from one end of the loop and a T-shaped anchor extending from the other end.

5. A device as set forth in claim 4, character-

ized by forming the tying member flat with the respective obverse and reverse surfaces parallel.

6. A hair curler including a body having a pair of jaws, said body and jaws being formed flat and of plastic material, each of said jaws having at the free end a notch and said body having a notch for each of the notches in the jaws.

7. A hair curler including a flat body having a pair of flat jaws extending from one end, each of said jaws having a notch in its free end, said body adjacent each side and at the end opposite said jaws having a notch, the material of said body adjacent the notches therein being inclined, the inclined part on one side of the body being in one direction and on the opposite side in the opposite direction.

8. A hair curler including a flat substantially rectangular body having a pair of jaws extending from one end thereof, said jaws having a pair of parallel slightly spaced walls merging at the other end into arc-shaped walls extending to the free ends of the jaws, each of said jaws at the free end having a notch extending longitudinally of the jaws with the material on the outer edge projecting beyond the material on the inner edge, said body at the end opposite said jaws having a notch near each side and an endless rubber band member adapted to have a portion fitted in each of the first-mentioned notches and a second portion in the corresponding notch in the body.

9. In a hair curler, the method of removing a tying member formed with a resilient body having a T-shaped flexible head at one end and a handle at the other end interlocked therewith consisting in pulling the handle longitudinally of the curled hair away from the T-shaped head for disengaging the handle from the head, swinging the handle to the opposite end of the curled hair, and then pulling the handle body and T-shaped head in the opposite direction until all parts of the tying member are removed from the hair.

10. In a hair curler, a flat substantially rectangular shaped curler body formed with a pair of substantially parallel jaws normally resiliently held juxtaposed and provided with a group of openings for permitting the jaws to resiliently move toward and from each other, one of said openings being at the juncture of said jaws, one opening in each jaw near the first opening, and a pair of spaced openings in said body near the first mentioned opening.
